UNITED STATES PATENT OFFICE.

HOWARD J. BENNETT, OF OPPORTUNITY, WASHINGTON.

TOY HOUSE.

1,258,086.

Specification of Letters Patent.

Patented Mar. 5, 1918.

Application filed October 13, 1917. Serial No. 196,413.

To all whom it may concern:

Be it known that I, HOWARD J. BENNETT, a citizen of the United States, residing at Opportunity, in the county of Spokane and 5 State of Washington, have invented certain new and useful Improvements in Toy Houses, of which the following is a specification.

The present invention relates to improvements in toy houses, of the knock down type, 10 and preferably made of cardboard or similar material, with interlocking features for securing the members of the house or structure together.

15 The primary object of the invention is the provision of a toy of this type which will be attractive, and educational, so far as concerns children, and which may be compactly arranged for storing and shipping 20 which may be quickly and easily erected, and which is stable and durable in its construction, and to this end the invention consists in certain novel features, and combinations and arrangements, of parts, as will 25 be hereinafter more fully described and claimed.

In the accompanying drawings one complete example of the physical embodiment 30 of the invention is illustrated, made and arranged according to the best mode so far devised for the practical application of the principles of the invention. The structure as illustrated in the drawings has been reduced to practice and proven highly suc- 35 cessful in use.

Figure 1 is a perspective view of the toy house complete, partly broken away for convenience of illustration.

Fig. 2 is a view in elevation of the front 40 wall.

Fig. 3 is a view of the transverse partition.

Fig. 4 is a view of the longitudinal partition.

45 Fig. 5 is a longitudinal sectional view of the toy house.

Fig. 6 is a perspective view of the package into which the parts of the house are formed for storing or shipping.

50 Fig. 7 is an enlarged detail view showing one of the wall locking corners and a part of the ceiling.

Fig. 8 is a detail view showing one form of ornamentation for the walls of the house.

55 In the preferred embodiment of the in-

vention as illustrated in the drawings, the structure is made up of card board, pressed paper, or similar material, and is supported from a foundation member which comprises the floor indicated by the numeral 1, and 60 the four sills designated 2, and arranged in rectangular form, to support the structure when it is erected, and to form a receptacle into which the remaining portions of the structure may be deposited for packing and 65 shipping, as indicated in Fig. 6.

The flooring of the receptacle, which forms the base or foundation of the house, 70 is slotted as at 3, 3, and these slots extend transversely of the house and are preferably located at the four corners, intermediate of the front and rear edges of the base, and approximately midway the depth of the house base, and an additional transverse slot is provided in the flooring at approximately the center of the house base. 75 In addition to these enumerated, transversely extending slots 3, a pair of longitudinally extending slots 4 are provided near the front and rear ends of the base, 80 and these slots 3 and 4 are designed to receive locking members on the superstructure of the house which includes the front wall 5, rear wall 6, side walls 7, transverse partition 8, and longitudinal partition 9. 85 In the several figures of the drawing it will be observed that these vertically arranged members of the house are each fashioned with depending tongues 10 at their lower edges, and that the tongues register 90 with the slot 3 and 4, so that when the walls and partitions are erected these tongues are passed through the complementary slots, and the vertical members are locked to the base by the utilization of wedge keys 11 95 passed through slots 12 in the several tongues 10. Thus, in erecting the structure the four walls and partitions are disposed in their proper places with their tongues projecting through their complementary 100 slots in the floor, and when locked with the wedge keys, they form four rooms or compartments. The partitions are interlocked by means of the two slots 13 and 14, the former in the lower portion of the transverse partition 8 and the latter in the upper portion of the longitudinal partition 9, the two partitions providing a cruciform structure in a well known manner. The front 105 and rear walls respectively, are braced by 110

55 In the preferred embodiment of the in-

being fitted up in the slits 15 15 at the respective ends of the longitudinal partition 4 (see Fig. 4 especially).

The roof structure as shown, is preferably 5 of the gable type and comprises the front section 16, rear section 17 and the two side sections 18, 18, disposed on slanting lines as seen in Figs. 1 and 5, and these sections are sustained and supported from the vertical 10 walls and partitions of the house, through the utilization of the kerfs 19, cut in the lower edges of the roof sections, and the tongues 20 with their inclined kerfs 21. The tongues or extensions 20 are formed on the 15 front and rear walls and on the two partitions, only, and as seen in Fig. 1 there are provided three supporting extensions at the sides of the house and one each at the front and rear, so that when the roof sections are 20 placed in position by interlocking the kerfs 19 with the inclined kerfs 21, they will be securely fastened in place at their lower edges. At the adjoining edges of the 25 respective roof sections, the sides 18 18 are fashioned with front and rear mortises or recesses 22, and the front roof section 16 and rear roof section 17 are each formed with end tenons 23 fitting in the mortises 22, to strengthen and brace the roof structure.

30 A ceiling is provided for the four rooms of the house by fitting the boards 24, 24 on the top edges of the front and rear walls and two partitions, which are cut-away for the purpose, as indicated at 25 in Figs. 2, 3, 35 4, and 7.

For compactly storing the members of the house when packing or shipping, the base is inverted and the flat members are nested therein, and then retained therein by the two 40 bands 26 26 (as in Fig. 6) which are shown as extending across the open base with their ends pasted to the inner faces of the side sills 2, 2.

The walls are of course provided with the 45 usual door and window openings, and the partitions are also fashioned with openings to provide communication between the rooms, and the walls may be decorated or 50 ornamented in any suitable manner. If desired, the window and door openings, wall designs, etc., may be imprinted in the card-

board or material of which the walls are constructed, and the colors may be added thereto by a child, using his or her own ideas as to color schemes, for both the interior and 55 exterior decoration, as for instance, siding or brick may be represented on the side walls, tile or brick for the porch floor 27 (Figs. 1 and 5) shingles for the roof, and suitable interior decorations as shown for 60 the inside walls of the house. If the structure is to be used only temporarily, the wedges 11 may be omitted, and the superstructure will be braced by its interlocking 65 features and supported on the base by tongues 10, but for a permanent structure, the wedges or keys 11 are used.

What is claimed herein is:—

1. The combination in a toy house with a 70 base portion slotted as described, the four walls, and a pair of diametrically arranged partitions, all secured to the slotted base and having tongues projecting therethrough, of roof sections having edge slots, and upper, end, extensions on some of said walls, and 75 the partitions, having inclined slots to receive the slotted roof sections.

2. The combination in a toy-house superstructure with walls having upper, end, extensions provided with inclined slots, of 80 roof sections having edge slots fitted in the slotted extensions and the adjoining edges of said roof sections having a mortise and tenon joint for locking said sections together.

3. The combination in a toy house with a 85 base portion slotted as described, the four walls, and a pair of diametrically arranged interior partitions, locking tongues on said members projecting through the slotted base 90 and locking wedge keys therefor, of roof sections having mortise and tenon joints at their adjoining edges and provided with slots at their lower edges, and extensions with inclined slots at the upper ends of some 95 of the walls and said partitions to receive the slotted roof sections, said walls and partitions having decorative designs impressed thereon.

In testimony whereof I affix my signature. 100

HOWARD J. BENNETT.
